HOT DISH HOLDER

Trinidad B. Oropeza, 7222 E. Beverly Drive,
Tucson, Ariz. 85710

Filed Oct. 1, 1973, Ser. No. 402,071

Term of patent 14 years

Int. Cl. D7—06

U.S. Cl. D7—130

FIG. 1 is a front perspective view of a hot dish holder embodying my new design;

FIG. 2 is a top plan view thereof;

FIG. 3 is a bottom plan view thereof;

FIG. 4 is an elevational view representing the identical front and back view thereof; and

FIG. 5 is an elevational view representing the identical right and left views thereof.

I claim:

The ornamental design for a hot dish holder, substantially as shown and described.
